PUSH BENCH

Hans Wohlnick, Dusseldorf, Germany, assignor
to Schloemann Aktiengesellschaft, Dusseldorf,
Germany, a corporation of Germany

Application August 27, 1934, Serial No. 741,646
In Germany September 1, 1933

1 Claim. (Cl. 205—4)

My invention relates to push benches for making tubes and other hollow articles, and more particularly to the means provided in such benches for guiding the mandrel and its carrier.

5 It has already been proposed to employ guiding means for that purpose which are moved sideways by the advancing rack bar which drives the mandrel and its carrier to make room. Means of that kind are subject to rapid wear or even
10 breakage by the heavy shocks and impacts from the rack bar. A further drawback is that these guides engage the mandrel and its carrier at intervals only and not along their entire length.

To obviate these drawbacks, stationary guide means have already been proposed which extend all over the length of the mandrel and its carrier and have the form of a tube or a hollow prism. With this type of guide means, the mandrel shaft which is enclosed by them cannot directly be engaged by the rack bar so that an intermediary member was necessary to couple the rackbar with the mandrel carrier which member extended through a slot in the stationary guide. The rackbar and the mandrel carrier could therefore
25 not be arranged in the same axis and the force exerted on the mandrel carrier by the advancing rackbar was eccentrically transmitted to the former, thus subjecting the latter to a momentum which was considerable in view of the heavy
30 forces required for pushing the mandrel and the work piece through the dies. For this reason, the rackbar and its bedplate had to be made very large to take up this momentum whereby they became very expensive.

35 It is further old to arrange two rack bars side by side and transmit their movement by a sort of crosspiece connecting them. In this construction also the rack bars were not symmetrically arranged with respect to the axis of the mandrel and its carrier and therefore the force was eccentrically transmitted to them. Furthermore, this arrangement called for a very wide bed plate to accommodate the two opposite rack bars which is a further drawback.

45 In another construction, there is one rack bar with teeth on opposite sides and meshing with two pinions. In this instance, the mandrel carrier can be symmetrically arranged with respect to the rack bar, but it is not possible there, to
50 provide stationary guides so that movable guides

had to be used which had, of course, the above mentioned disadvantages.

My invention has for its object to provide a push bench in which the guides of the mandrel carrier are stationary and in which at the same time these parts are so arranged with respect to the rack bar that the force is transmitted to the mandrel carrier without causing a detrimental momentum.

According to this invention, I make the rack 10 bar of H shaped cross section, the flanges of the H being externally provided with teeth and stationary guides being arranged symmetrically to the rack bar and in the spaces between these flanges at both sides of the web of the H. 15

In the annexed drawing, on which I have illustrated an embodiment of my invention,

Fig. 1 is a cross section of the bench,

Fig. 2 a side elevation, and

Fig. 3 a plan view of the rack-bar and the driving pinions. 20

According to my invention, the rack bar 1 of the novel push bench is H shaped, and is supported by a bed plate 2. 3 and 4 are guides for the mandrel carrier 5, arranged in the spaces between the flanges of the H and at both sides of its web. The guides are stationary in the sense, that they are not moved by the advancing rack bar, but are so constructed as to be readily removable when desired. The flanges of the rack 30 bar are toothed on their outer sides and in mesh with pinions 6 (Fig. 3).

As the teeth are arranged symmetrically with respect to the axis of the mandrel and its carrier, the force will be transmitted to the former without any momentum. 35

The mandrel and the dies are not represented here as they form no part of my invention and can be of any desired type.

I claim as my invention:

In a push bench for making tubes and other hollow articles, a mandrel carrier, a rack bar for advancing said carrier, said rack bar being symmetrically arranged with respect to said carrier and having the shape of an H, teeth on the outer 45 sides of the flanges of said rack bar and stationary guide members for said carrier in the spaces between the flanges at both sides of the web of the rack bar.

HANS WOHLNICK. 50
